UNITED STATES PATENT OFFICE.

THEODORE HAVILAND, OF AMBAZAC, FRANCE.

DESIGN FOR A PLATTER.

SPECIFICATION forming part of Design No. 24,513, dated July 30, 1895.

Application filed May 28, 1895. Serial No. 551,002. Term of patent 7 years.

To all whom it may concern:

Be it known that I, THEODORE HAVILAND, a citizen of the United States, residing at Am-
bazac, in the Department of Haute-Vienné and
Republic of France, have invented and pro-
duced a new and original Design for a Dish;
and I do hereby declare the following to be
a full, clear, and exact description of the same,
reference being had to the accompanying
drawings, forming a part thereof.

Figure 1 is a face view of a low dish or
platter, having a well or reservoir at both
sides and ends of the dish or platter, making
in all four wells or reservoirs, with orna-
mental scrollwork running from one well or
reservoir to the other. Fig. 2 gives a sectional
view of the dish or platter, showing the depth
of the wells or reservoirs.

At the base of the dish or platter is a pro-
jecting rim D, which serves as a foot or stand-

ard, and an inner rim d to support the center
of the dish or platter.

The principal feature of my design con-
sists of a low dish or platter having four wells
or reservoirs A A A A to receive the juices or 25
gravy of the meat, conveniently arranged at
the sides and ends of the dish or platter.
The center of the dish or platter is slightly
raised, in order to give a direction to the juices
or gravy exuding from the meat toward the 30
wells or reservoirs.

What I claim is—

The design for a dish or platter, as herein
shown and described.

In testimony whereof I affix my signature 35
in presence of two witnesses.

THEODORE HAVILAND.
